UNITED STATES PATENT OFFICE

2,104,969

CARTON

Martin Burger, Morris, Ill., assignor to Self-Locking Carton Co., Chicago, Ill., a corporation of Illinois

Application January 4, 1935, Serial No. 325

1 Claim. (Cl. 229—29)

The present invention pertains to cellular cartons of the type customarily employed for holding fragile articles such as eggs, and has particular reference to an improved construction for the production of cartons of the so-called 3 x 4 style.

Egg cartons are of two general types. As an example of the first type, reference is made to Troyk Patent No. 1,766,155. This carton is of the 2 x 6 type, in which the eggs are placed in two adjacent rows separated by a longitudinal partition. The eggs are supported above a surface upon which the carton is positioned by means of a cushion bottom. The other type of egg carton is of the so-called 3 x 4 type, in which a flat bottom box is provided with a separate cellular filler consisting of strips secured together in foldable relation to provide twelve compartments, three along one dimension of the carton and four along the other.

A principal object of the present invention is to provide a one-piece 3 x 4 carton which is manufactured easily and provided with a cushion bottom.

An additional object is the provision of a carton having the combined advantages of the two types of cartons known heretofore.

A further object is the provision of a 3 x 4 carton in which is employed a minimum quantity of material and at the same time a cushion bottom is provided.

These and other objects will be evident upon consideration of the following specification, in which is described a preferred embodiment of my invention and by reference to the accompanying drawing, in which

Fig. 1 is a perspective view of a 3 x 4 carton constructed in accordance with my invention, the carton being shown in erected or set-up condition;

Fig. 2 is a longitudinal section taken along line 2—2 of Fig. 1;

Fig. 3 is a fragmentary top view of the carton taken along line 3—3 of Fig. 4; and

Fig. 4 is an end view of the carton.

As is stated hereinbefore, the usual style of 3 x 4 carton which has met with commercial success consists of a flat bottom carton having a separate filler or insert which may be distended from collapsed condition into rectangular shape in which the filler provides twelve cellular compartments, three along one dimension of the carton and four along the other. This style of carton offers some competition to the more desirable 2 x 6 carton of the type described in the be-

forementioned Troyk patent. However, it has been necessary to sell the 3 x 4 carton at several dollars a thousand less than the 2 x 6 carton. The inability to obtain a better price for the standard 3 x 4 carton is primarily due to the fact that the carton is not rigid, that is, it can be twisted easily, and also the carton does not provide a cushion bottom for the prevention of breakage of eggs. So great has been the objection to this style of 3 x 4 carton that it has not been used for shipping purposes. On the contrary, the standard 3 x 4 carton ordinarily is used by the retailer for dispensing eggs from the counter.

In the prior art, attempts have been made to provide a cushion style 3 x 4 carton, but these attempts have met with failure and no such cartons are on the market. A principal example of such prior attempts to provide a cushion bottom 3 x 4 carton is to be had in the carton described in Wilson Patent No. 905,615, issued December 1, 1908. In this Wilson patent a blank is folded in the form of a series of V-shaped channels separated from each other by longitudinally extending ridges. The egg-receiving channels are divided up into a plurality of cellular compartments by separated inserts, which extend transversely through the blank and are locked to the outside walls thereof by means of hooks.

In accordance with my invention I have provided a 3 x 4 carton in which is combined the advantages of this type of structure, as well as the advantages of the cushion bottom 2 x 6 cartons known heretofore. As shown in the drawing, the carton is constructed by suitably cutting, scoring and folding a single blank of paper board or the like to form cover-locking hooks 10, a cover-locking strip 11, and a cover portion 13 separated from the strip 11 by means of a score line 12. To the opposite end of cover 13 is integrally attached a rear wall 15, separated from the cover by means of a score line 14. A rear bottom section 17 is connected to the wall 15 along a score line 16 and extends upwardly and inwardly toward the center of the carton, as shown particularly in Fig. 4. This rear bottom section 17 terminates at a division point of about one-third the width of the carton, and then extends downwardly from score line 18 to form the rear side 19 of an intermediate V-shaped channel. The section 19 extends downwardly to the level of the bottom of the carton at the center of the carton, and is joined at a certain score line 20 by an upwardly and outwardly slanting front section 21 of the intermediate V-shaped channel. This

front section 21 of the intermediate channel is joined along score line 22 by a front bottom section 23 which extends downwardly and is joined along a score line 24 to a front wall 25.

- 5 A series of cross partitions 26 are joined to the front wall 25 by means of integral triangular tabs or hinge portions 27. The opposite upper edges of the cross partitions likewise are provided with triangular tabs or hinge portions 28
10 which secure the cross partitions to an attaching strip 29.

In manufacture, the blank from which the carton is produced is properly cut and scored. Thereafter the blank is folded along the score
15 line 20 of the intermediate channel. A score line 30 is provided longitudinally of the cross partitions and in the central portion thereof and the cross partitions are folded along the score line. A suitable quantity of glue is applied to the
20 attaching strip 29 and the latter is pressed against the bottom wall to complete the assembly of the carton.

In accordance with my invention the bottom section is provided with three longitudinally extending V-shaped channels separated from each other by upwardly extending ridges, and this bottom is locked in secure relation with the cross partitions in such a manner that the bottom is rigid. In the embodiment of my invention shown
25 in the drawing the cross partitions are provided with outer downwardly extending prongs 31 adjacent the rear of the carton and similar downwardly extending prongs 32 adjacent the front wall of the carton. Prongs 31 are provided with
30 inwardly facing hook portions 33 which extend through openings 34 in the rear bottom section 17 and engage this section to maintain the same in suspended condition. Similar hooks 35 are provided on the front prongs 32 and these
35 hooks engage the front bottom section 23 through openings 36. When eggs are placed in the outer channels of the carton the sections 17 and 23 tend to be pressed toward the inner portion of the carton. To maintain the central channel
40 in proper shape I have provided downwardly extending projections 37 on the central portion of the cross partitions, and these projections 37 fit against the downwardly extending walls 19 and 21 of the intermediate longitudinal channel.

50 It will be seen that my carton does not employ longitudinal partitions of the type used heretofore. That is, in the 2 x 6 cartons known heretofore the ridge portion which divides the carton into two longitudinal sections of cells extends upwardly above the center of eggs placed in the carton, whereby to prevent the eggs from coming in contact with each other, it being thought that such a longitudinal partition was necessary to prevent the eggs from breaking.

55 60 However, it has been my discovery that when the bottom section is constructed as described herein it is not necessary that the partitions between the longitudinally extending cells extend upwardly above the center of the eggs. In fact, cartons of the type described herein have been packed with eggs and shipped under adverse

conditions with the surprising result that no eggs are broken, even though, as will be seen from the drawing, eggs placed in the carton do not have paper material between their widest portions.

5 It will be seen from Fig. 4 that wall 21 has a greater angle to the horizontal than does wall 17 and likewise 19 has a greater angle to the horizontal than does wall 23. This relation tends to cause the eggs in the outer longitudinal channels to spring away from the center of the carton, thereby protecting the eggs against contact with the eggs in the central longitudinal channel or compartment.

Opposite the lower projections 37 on the cross partitions are provided cover-protecting projections 38 which extend upwardly adjacent the under side of the cover and press or protect the latter against blows or jars. It will be seen that when pressure is applied to the cover this pressure is transferred through the cross partitions to the downwardly slanting walls 19 and 21. As the hooks 33 and 35 are spaced apart a considerable distance, it is possible to construct the upper cover-supporting projections 38 with a substantial quantity of material. That is, the cover-supporting projections 38 extend beneath the carton for a distance greater than the width of the central channel.

30 As stated hereinbefore, the carton is constructed and shipped in collapsed condition by folding the body portion along score lines 20 and 30. The carton is easily erected by the use of a suitable block which acts to rotate the cross partitions from their collapsed horizontal position into erect 35 position at right angles to the bottom section and walls of the body portion of the carton. By grasping the bottom of the carton along the contiguously positioned walls 19 and 21, the bottom of the carton may be pressed into interlocking 40 engagement with the hooks 33 and 35 without difficulty, since the walls 19 and 21 afford a convenient outwardly extending handle.

45 While my invention has been described with particular reference to a preferred embodiment thereof, it will be understood that changes and variations from the described structure are possible without departing from the spirit of the invention, and all such modifications are intended to be included in the appended claim.

50 I claim:

A carton of the type described, comprising front and rear walls, cross partitions hinged to the upper portion of said walls, a bottom portion having inwardly and upwardly inclined outer sections and downwardly and inwardly inclined intermediate sections forming three longitudinal channels, means for supporting said bottom to said cross partitions, downwardly extending projections on the central portion of said cross partitions engaging the intermediate sections of said bottom portion, and upwardly extending cover-engaging projections opposite said downwardly extending projections.

55 60 MARTIN BURGER. 65
